UNITED STATES PATENT OFFICE.

WALTER F. HAMMEL, OF CHICAGO, ILLINOIS, ASSIGNOR TO ESTHER S. HAMMEL, OF CHICAGO, ILLINOIS.

SAFETY ENVELOPE.

1,406,456.

Specification of Letters Patent. Patented Feb. 14, 1922.

Application filed August 17, 1920. Serial No. 404,157.

To all whom it may concern:

Be it known that I, WALTER F. HAMMEL, a citizen of the United States, and a resident of Chicago, in the county of Cook and 5 State of Illinois, have invented certain new and useful Improvements in Safety Envelopes, of which the following is a specification.

My present invention relates in general 10 to envelopes, and more particularly to what are known as safety-envelopes, and has particular reference to the provision of an envelope having means for so sealing it that it may not be opened to any extent without 15 out such damage to the sealing means as will render any slight tampering with the seal obvious upon casual inspection.

The principal objects of my present invention are the provision of an improved 20 envelope specially adapted for permanent closure by means of sealing wax, or the like, and one so characterized that the wax employed for sealing engages not only an outer portion of the envelope structure proper 25 but also another portion carried by such outer portion and reached therethrough; the provision of an envelope characterized generally by the provision of a socket for the reception of sealing wax, and more particu- 30 larly one wherein such socket is so arranged that the sealing wax engages an underlying surface of the envelope structure; the provision of an envelope characterized generally by the provision of improved auxili- 35 ary means for holding down the outer or sealing flap, and more particularly one wherein such auxiliary means is adapted for engagement with the sealing wax used for sealing the envelope; the provision of an 40 envelope characterized generally by the provision of improved means for engagement with sealing wax and particularly one adapted for the employment of a relatively thin film of wax which while adequate for 45 such purpose will easily break in the event of any tampering with the seal; the provision generally of an improved form of expandible envelope and more particularly one of the class referred to adapted for use 50 as a safety envelope irrespective of the volume of its contents; together with such further and additional objects as may hereinafter appear.

While structures embodying my present 55 improvements have a wide range of utility,

I have, for purposes of illustration, illustrated them as embodied in an envelope adapted for the transmission of such relatively bulky documents as coupon bonds which may be forwarded through the mails 60 or by express either singly or in sets.

In the accompanying drawings, therefore,

Figure 1 is an elevational view of the back of an envelope embodying my present improvements; 65

Figure 2 is a fragmentary view of the envelope of Figure 1, the retaining and closing flaps being shown in open position;

Figure 3 is a sectional view taken on the 70 line 3—3 of Figure 2; and

Figure 4 is a sectional view of the envelope of Figure 3, but showing the flaps in closed position, the same being taken on line 4—4 of Figure 2. 75

On inspection of the drawing, it will be apparent that my improved safety envelope structure includes a face portion, 10, a back portion, 11, comprising a back flap, 12, and end flaps, 13, 13, and a closing flap, 14, the back flap, 12, being provided with an inwardly turned enclosure retaining flap, 15, for a purpose hereinafter to be described.

The end flaps, 13, preferably overlie the back flap, 12, and are fixed thereto by the 85 employment of adhesive material in the usual manner.

The closing flap, 14, has a gummed surface, 16, extending marginally not only across the entire length of the flap but also 90 toward the end flaps, 13, as indicated at 17 in Figures 1 and 2, (the extent of the gummed surface being also indicated by the dotted line 18 in Figure 1,) whereby the envelope may be sealed against interference 95 with its contents.

As an additional means for securing the closing flap, 14, against both the end flap, 13, and the back flap, 12, the closing flap, 14, is provided, preferably at each end, 100 with an aperture, 19, adapted to cooperate with an auxiliary closing member, also fixed at each end of the envelope, and now to be described.

The closing member, 20, as here shown, 105 comprises an elongated strip of material, preferably formed of thin sheet metal which may readily be bent.

This auxiliary extension, 20, is fixed to the back, 11, of the structure, and as supple- 110

mental means to prevent separation of the end flap, 13, from the back flap, 12, is preferably so fixed to both of the flaps, 12 and 13, that they are joined together.

- 5 To accomplish this fixation of the member, 20, to the flaps, 12 and 13, and to permit a desired swinging movement of the member, 20, I find it convenient to use a circular eyelet, 21, which thus serves not only 10 as a means for attachment but also as a pivot to afford any desired variation of the member, 20, relatively to the aperture 19.

Furthermore, as will be evident on inspection of Figure 2 of the drawing, the 15 point where the eyelet passes through the member, 20, and the flaps, 12 and 13, is preferably arranged in offset relation to the aperture, 19, in such a manner that the eyelet, 21, is not disclosed when the closing flap, 20 14, is brought against the back flap, 12, and the end flap, 13, in closing the envelope, but is also in such offset relation to the aperture, 19, that it is fully covered by the back flap, 14.

- 25 The aperture 19, is preferably enlarged beyond the immediate necessity of forming a passage therethrough for the fastening member, 20, to the end that such fastening member may be bent in such a manner as 30 may be convenient to occupy more or less of the space formed by such aperture, 19, in order, in the first place, that the member, 20, may hold down the closing flap, 14, against opening, and in the second place, 35 that said aperture, 19, may not only form a socket for the reception of the bent-over portions of the member, 20, but also for the further reception of a seal formed of sealing wax or the like.

- 40 As will be clear on examination and comparison of the closures made at the right hand and left hand ends of the envelope shown in Figure 1, the aperture, 19, is so arranged as not only to serve for engagement 45 with the fastening member, 20, but also to disclose underlying parts of the end flaps, 13, and back flap, 12, so that when molten sealing wax is directed into the socket, 19, it not only engages the previously bent auxiliary fastening member, 20, but also both 50 of the underlying flaps, that is the back flap, 12, and the adjacent end flap, 13. Furthermore, inasmuch as the closing flap, 14, is lifted slightly from the adjacent portions 55 of the back flap, 12, and the end flap, 13, by the thickness of the member, 20, the molten sealing wax will flow under the closing flap, 14, and on to subjacent portions of the back flap, 12, and end flap, 13, whereby they may 60 be additionally sealed.

From the foregoing description, it will be understood that owing to the fact that the various bent portions of the member, 20, (see left-hand end of Figure 1) lie in different 65 planes, when the molten sealing wax is di-

rected into the socket, 19, and the usual metallic seal pressed into such sealing wax, there will be but a relatively thin film of sealing wax covering the member, 20, and in any event whatever be the quantity of wax 70 employed, it is in non-detachable engagement with the angular bent portions of the closing member, 20, and consequently any attempt to remove the seal in order to open the envelope will be practically certain to 75 break or distort the wax seal and similarly that the wax seal may not be removed from the envelope owing to the fact that the member, 20, is anchored therein.

By virtue of giving the opening, 19, an 80 elongated form and also providing the member, 20, with a somewhat extended length, the envelope shown in the drawing is provided with a capacity for quite a considerable expansion, without sacrifice of any of the points of benefits and advantages hereinbefore pointed out, the aperture, 19, serving within relatively large limits to disclose underlying parts of the back flap, 12, and end flap, 13, regardless of the bulk of the 90 contents of the envelope.

Having thus described my invention and illustrated its use, what I claim as new and desire to secure by Letters Patent is—

1. A device of the character described comprising, in combination, a receptacle and means for closing the receptacle, one of said members having an enlarged opening therethrough, and the other of said members having an extension arranged in said opening, 95 said opening and extension being correlated for the reception of a sealing means adapted to seat in said enlarged opening and to extend between said receptacle and the means for closing the receptacle.

2. An envelope comprising, a body portion and a closing flap, one of said members being provided with an opening, and an extension secured to the other member at a distance from the opening and arranged to pass 100 therethrough.

3. An envelope comprising, in combination, a body portion and a closing flap, one of said members being provided with an enlarged socket and the other of said members being provided with an extension, slightly separating said members and overlying the edge of said socket, and the two members being adapted to receive a seal disposed in the socket and engaging both the outer member and the extension and projecting into the space between the inner and outer members.

4. An envelope comprising, in combination, a body portion and a closing flap, one 115 of said members being provided with an enlarged socket and the other of said members being provided with an auxiliary metallic extension arranged in said socket and overlying an edge thereof, said extension being 120 130

attached to the underlying member at a point spaced away from said socket but under the flap, and the two members being adapted to receive a seal disposed in the 5 socket and engaging both the outer member and the extension.

5. An envelope comprising, in combination, a body portion and a closing flap, one of said members being provided with an enlarged socket and the other of said members being provided with an auxiliary metallic extension arranged in said socket and overlying an edge thereof, said extension being attached to the said member at a point 10 spaced away from said socket but under the flap, and the two members being adapted to receive a seal disposed in the socket and engaging both the outer member and the extension.

20 6. An envelope comprising, in combination, a body portion including side flaps and a back flap, and a closing flap, said closing flap being provided with an enlarged socket, and one of the side flaps and the back flap 25 overlapping each other, and an auxiliary metallic extension fixed to overlapping portions of said side and back flaps, and arranged in said socket, and said closing flap overlying the point of fixation of said extension to said overlapping portions, and the 30 socket and the flap underlying the socket being adapted to receive a seal engaging said extension.

35 7. An envelope comprising, in combination, a body portion including side flaps and a back flap, and a closing flap, said closing flap being provided with an enlarged socket, and one of the side flaps and the back flap 40 overlapping each other, and an auxiliary metallic extension fixed to overlapping portions of said side and back flaps, and arranged in said socket, and said closing flap overlying the point of fixation of said extension to said overlapping portions and 45 said socket overlying both said side and back flaps, and the socket and the flaps underlying the socket being adapted to receive a seal engaging said extension.

50 8. A device of the character described comprising, in combination, a receptacle and means for closing the same, means extending from the receptacle and engaging the closing means, said engaging means being spaced from the underlying portion of said receptacle, and said closing means and engaging means receiving a sealing medium entering the space between said latter means and the 55 underlying portion of the receptacle.

60 9. An envelope comprising a body portion and a flap, one of said members being provided with an opening and means for spacing said flap from said body portion adjacent said opening whereby a fluid sealing means positioned in the opening will flow 65 into the space between the body and the flap.

10. A device of the character described, comprising, in combination, a body portion, a closing flap therefor, a flexible holding member extending from the body portion to a socket or recess in said flap, said member being in spaced relation to the underlying portion of the body, and a sealing means applied over said member and socket and having a part lying between the member and body, and between the flap and said body. 70

75 11. An envelope comprising a body portion and a flap, one of said members being provided with an opening spaced from the underlying body portion, whereby a fluid sealing means positioned in the opening will 80 flow into the space between the body and the flap.

85 12. In a device of the class described, in combination, an envelope having a body and a closing flap provided with a socket, a flexible element anchored to the body at a point spaced from the socket and adapted to extend to the socket and overlie one edge thereof to form a space between the flexible element and the underlying portion of the 90 body, and a sealing means engaging over said socket and flexible element and lying between the latter and the body and between said body and the closing flap.

95 13. An envelope, comprising, in combination, a body portion including a side flap and a back flap, and a closing flap, overlapping part of the back flap, and said closing flap being provided with an enlarged socket exposing portions of the underlying side 100 flap and back flap whereby the closing flap, back flap and side flap can be united by a single seal.

14. An envelope comprising, in combination, a body portion and a closing flap, one 105 of said members being provided with an enlarged socket to expose a substantial portion of the parts therebeneath and the other member being provided with an auxiliary portion passing freely through said socket and occupying but a small part of the area of the socket whereby a seal covering the socket will also engage the parts exposed therebeneath as well as the auxiliary portion, thus 110 securely sealing the parts against opening. 115

15. An envelope comprising, in combination, a body portion and a closing flap, one of said members being provided with an enlarged socket to expose a substantial portion of the parts therebeneath and the other 120 member being provided with means to the side of said socket for spacing the closing flap from the body portion whereby sealing means poured onto said socket will work its way down between the closing flap and the body of the envelope.

16. In a device of the class described, in combination, an envelope having a body and a closing flap provided with a socket, a flexible element anchored to the body at a point 130

spaced from the socket and adapted to extend through the socket from a position beneath the closing flap to a position above the closing flap, the socket being substantially larger than the flexible element, and a sealing means engaging over said socket and flexible element for maintaining the envelope in closed position.

17. An envelope comprising, a body portion and a closing flap, one of said members

being provided with an opening, and an extension secured to the other member at a distance from the opening and arranged to pass therethrough, said extension being positioned between the body and the flap and having its free end passing through the opening.

In testimony whereof I have hereunto signed my name.

WALTER F. HAMMEL.
